ANIMAL EAR TRIMMER

Filed July 2, 1949

UNITED STATES PATENT OFFICE

2,556,036

ANIMAL EAR TRIMMER

Harlan E. Jensen, Shaker Heights, Ohio

Application July 2, 1949, Serial No. 102,864

5 Claims. (Cl. 128—305)

1

This invention relates to animal ear trimming devices and, as its principal object, aims to provide an improved device of this character which is easy to operate and accomplishes an efficient trimming action and which is composed of a small number of parts adapted to be economically produced and assembled.

Another object of the invention is to provide an improved ear trimmer comprising cooperating members, one of which has a guideway with a knife carrier slidably therein, and the other is a channeled member forming both a clamping jaw for holding the ear to be cut and a cover for the knife during its cutting stroke.

A further object is to provide an improved ear trimmer comprising cooperating jaw and body members adapted to clamp an ear therebetween and a knife carrier slidable in a guideway to the body member, and in which the body member has spaced guide elements engaged by the jaw member and mounting the latter thereon for relative clamping movement for holding the ear to be trimmed.

Still another object is to provide an improved ear trimmer of the character mentioned in which the guide elements of the body member are hollow arms and in which spring means mounted in such hollow guide arms act on the jaw member to shift the same relative to the body member.

As another of its objects this invention provides an improved ear trimmer of the character indicated in which the knife has a cutting edge disposed in rearwardly inclined relation to the direction of travel of the knife carrier during the cutting stroke so as to cause cutting of the ear by the knife being drawn thereacross with a slicing action.

It is also an object of the present invention to provide an improved ear trimmer of the character referred to which can be readily disassembled for cleaning and in which quick releasable connecting means is employed for detachably mounting the knife on the carrier.

The invention can be further briefly summarized as consisting in certain novel combinations and arrangements of parts hereinafter described and particularly set out in the claims hereof.

In the accompanying sheet of drawings:

Fig. 1 is a side elevation, with portions broken away, showing an ear trimming device embodying the improved construction;

Fig. 2 is an end view of the device;

Fig. 3 is a transverse vertical section taken

2

through the device substantially on section line 3—3 of Fig. 2;

Fig. 4 is a fragmentary side elevation showing the end of the carrier which is adapted for the mounting of a knife blade thereon;

Fig. 5 is a fragmentary edge view of such end portion of the carrier; and

Fig. 6 is a perspective view illustrating the use of the improved ear trimming device.

10 As one embodiment of the invention the drawing shows an improved ear trimmer 10 comprising, in general, a pair of cooperating jaw and body members 11 and 12 defining therebetween a clamping space or zone 13 in which a portion of an animal ear is adapted to be held, and a cutter bar 14 slidably movable in the body member 12 and carrying a knife 15 for cutting engagement with the clamped ear.

The body member 12 comprises an elongated member having a pair of hollow guide arms 16 and 17 formed thereon or connected therewith and located at or adjacent its ends. This body member is also provided with a longitudinally extending substantially straight or flat clamping face 18 formed on one side thereof and extending between the hollow guide arms 16 and 17. As shown in the drawing, the hollow guide arms 16 and 17 project from the body member 12 in substantially right-angular relation thereto and each of these arms has an opening 19 extending therethrough and defined, in part, by the flat side portions of these guide arms.

The jaw member 11 is in the form of an elongated member or bar disposed in substantially coextending relation to the body member 12 and having a substantially straight longitudinal clamping face 20 for cooperation with the clamping face 18 for holding an animal ear against the latter. The clamping face 20 is preferably, though not necessarily, provided with serrations 20a extending transversely thereof for more effectively gripping the ear. This jaw member has bearing portions or lugs 21 and 22 at the ends thereof which extend into the openings 19 of the hollow guide arms 16 and 17 for mounting the jaw member in the body member 12 and providing for movement of the jaw member toward and away from the clamping face 18. The jaw member 11 has a transverse thickness which corresponds with or is slightly less than the transverse width of the openings 19 of the arms 16 and 17 which permits the jaw member to be readily assembled on the body member 12 by inserting the ends of the jaw member in succession into the hollow arms.

45 50

The jaw member 11 is retained in assembled relation to the body member 12 by the engagement of the bearing portions 21 and 22 in the hollow guide arms 16 and 17 and is held against endwise shifting by pins 23 and 24 projecting from the jaw member and engageable with the guide arms. To permit assembly of the jaw member in the body member, the guide arm 16 is provided with an internal slot 25 through which the pin 23 can be moved. In assembling the jaw member in the body member, the end carrying the pin 23 is inserted into the guide arm 16 first, with the pin 23 moving through the slot 25, after which the other end of the jaw member can be inserted into the guide arm 17.

Springs 26 and 27 act on the jaw member 11 to normally urge the same toward the body member 12 for clamping the animal ear in the clamping space or zone 13. Each of the springs 26 and 27 is a flat spring having a pair of spaced upper and lower arms 28 and 29 extending into the opening 19 of one of the hollow guide arms. The upper spring arm 28 has an upturned retaining lug 28a at the end thereof which engages the top portion of the guide arm with a hook-like action and the lower spring arm 29 has a down-turned retaining lug 29a at the end thereof which engages in a transverse slot 30 provided in the top edge of the jaw member 11. The springs 26 and 27 are retained in assembled relation by their hook-like lugs 28a and 29a and also by reason of the fact that their paired arms 28 and 29 extend into the openings 19 of the guide arms 16 and 17. The upper arms 28 of these springs bear against the tops of the guide arms 16 and 17 and the lower arms 29 of the springs bear on the jaw member 11 so as to constantly urge the jaw member toward a closed or ear-clamping position.

As best seen in Figs. 2 and 3 of the drawing the body member 12 is provided with a channel or guideway 31 extending longitudinally therethrough and a longitudinal slot 32 forming an upward extension of the guideway and opening through the longitudinal clamping face 18. The cutter bar 14 is in the form of an elongated member which is longitudinally slidable in the guideway 31 and is provided with a handle element 33 which is adapted to be grasped for manually shifting the cutter bar longitudinally in the guideway. In this instance, the handle element 33 is in the form of a ring mounted on the projecting end of the cutter bar 14 and through which the operator can insert an index finger. The ring 33 can be connected to the cutter bar by having its ends engaged in openings 34 formed in the edges of the cutter bar.

At the end of the cutter bar 14 opposite to the handle element 33, this member is provided with mounting means for mounting the knife blade 15 thereon. The knife blade shown in this instance is a substantially straight flat blade having a substantially square end portion or heel 15a for engagement with the cutter bar 14 and a beveled cutting edge 15b on the portion of the blade which projects beyond or above the cutter bar. To accommodate the square heel portion 15a of the knife blade 15 the cutter bar is provided with a notch or recess 35 of a corresponding substantially square shape in one side thereof, as shown in Figs. 4 and 5, and in which the square heel portion of the knife blade has seating engagement.

It is desirable that the knife blade 15 be readily detachable from the cutter bar 14 for sharp-

ening or cleaning purposes or to permit it to be replaced by another such blade. For this purpose the knife blade 15 is provided with a pair of keyhole-shaped slots 36 and the cutter bar is provided with a pair of headed mounting pins 37. These slots and pins cooperate to form a quick-detachable bayonet connection by which the knife blade 15 is releasably mounted on the cutter bar. In mounting the knife blade 15 on the cutter bar the large ends of the keyhole slots 36 are applied to the pins 37 and the longitudinal movement of the knife blade in the direction to engage the pins in the narrow portions of the slots also move the square heel portion of the knife blade into seating engagement in the square recess 35 of the cutter bar.

With respect to the mounting of the knife blade 15 on the cutter bar 14 it will be observed that the portion of the blade having the cutting edge 15b thereon projects from the cutter bar so as to extend through the slot 32 of the body member 12 in spanning relation to the clamping space or zone 13 and when the cutter bar is moved longitudinally toward the right, as seen in Fig. 1, a cutting stroke will be imparted to the knife for severing the animal ear being held in the clamping space 13. It will also be observed that the knife 15 is mounted on the cutter bar so that its cutting edge extends in upwardly and rearwardly inclined relation with respect to the direction of the cutting stroke of the bar 14 so that during such cutting stroke the cutting edge 15b will be drawn across the clamped ear and will cut the same with a smooth, clean slicing action.

In addition to serving as a clamping element the jaw member 11 also forms a cover for the knife during the cutting stroke. For this purpose the jaw member 11 is of a hollow construction and has a slot or channel 38 extending longitudinally therethrough and opening downwardly through the clamping face 20. The channel 38 extends in opposed coextending relation to the slot 32 of the body member 12 so that the upwardly and rearwardly projecting portion of the knife 15 will be movable longitudinally through this channel during the cutting stroke. When the jaw member 11 is of this hollow construction it will be observed also that it will apply clamping pressure to the animal ear along two longitudinal lines located on opposite sides of the slot 32 and this will permit the knife 15 to cut the ear smoothly and cleanly along the full length of the clamped portion thereof.

Fig. 6 of the drawing illustrates the manner of using the trimmer 10 and shows the same applied to the ear 40 of a dog 41. In applying the device to the dog's ear the jaw member 11 is lifted or opened relative to the body member 12 in opposition to the action of the springs 26 and 27 to enlarge the clamping space 13. The portion of the ear 40 which is to be trimmed away is inserted into this clamping space and the jaw member 11 is then released to permit the springs 26 and 27 to shift the same toward its closed position for clamping the ear against the body member 12. The clamping pressure thus supplied by the springs 26 and 27 can be supplemented by manual pressure applied to the jaw member 11 by the operator's hand which grasps the device. While the ear 40 is thus clamped, the cutter bar 14 is moved quickly through a cutting stroke, as illustrated in dotted lines in Fig. 1, during which the ear will be cleanly cut by the knife 15. It will be understood, of course, that

this cutting operation is carried out while the animal is under the influence of an anesthetic, preferably a general anesthetic.

From the accompanying drawings and the foregoing detailed description it will now be readily understood that this invention provides an improved animal ear trimmer which is of such simple construction that it comprises a very small number of parts which can be economically manufactured and assembled. It will also be seen that the construction of the device is such as to permit it to be quickly disassembled for cleaning and sterilizing purposes and for sharpening or replacement of the knife blade 15. Additionally, it will now be understood that this trimming device is very easily operated and carries out the trimming operation very efficiently by producing a clean and accurate cut.

Although the improved ear trimming device of this invention has been illustrated and described herein to a somewhat detailed extent it will be understood, of course, that the invention is not to be regarded as being limited correspondingly in scope but includes all changes and modifications coming within the terms of the claims hereof.

Having thus described my invention, I claim:

1. An ear trimming device of the character described comprising, an elongated body member having a pair of spaced hollow guide arms thereon and a clamping face between said guide arms, said body member also having a channel extending therethrough and said channel having a slot extension opening through said clamping face, said guide arms being rigid with said body member and projecting at substantially right angles therefrom on the side thereof containing said slot extension, a jaw member having a clamping face in coextending opposed relation to the clamping face of said body member and end portions slideable in said hollow guide arms for floating movement of said jaw member toward and away from said body member, a slide movable along the channel of said body member, and a knife carried by said slide and movable thereby along said slot extension for cutting engagement with an ear held between the clamping faces of said jaw and body members.

2. An ear trimming device of the character described comprising, an elongated body member having a pair of spaced hollow guide arms thereon and a clamping face between said guide arms, said body member also having a channel extending therethrough and said channel having a slot extension opening through said clamping face, said guide arms being rigid with said body member and projecting at substantially right angles therefrom on the side thereof containing said slot extension, a jaw member having a clamping face in coextending opposed relation to the clamping face of said body member and end portions slideable in said hollow guide arms for floating movement of said jaw member toward and away from said body member, spring means engaged in said hollow guide arms and acting on said jaw member for shifting the same relative to said body member, a slide movable along the channel of said body member, and a knife carried by said slide and movable thereby along said slot extension for cutting engagement with an ear held between the clamping faces of said jaw and body members.

3. An ear trimming device of the character described comprising, a body member having a pair of spaced hollow guide arms thereon and a

clamping face between said guide arms, said body member also having a channel extending therethrough and opening through said clamping face, a jaw member having a clamping face in coextending opposed relation to the clamping face of said body member and end portions slideable in said hollow guide arms for movement of said jaw member toward and away from said body member, said jaw member being readily disengageable from said guide arms for removal of said jaw member from said body member, a slide movable along the channel of said body member, a knife carried by said slide and movable thereby for cutting engagement with an ear held between the clamping faces of said jaw and body members, and spring means engaged in said guide arms and acting on said jaw member for urging the same toward said body member, said spring means forming a releasable connecting means for releasably retaining said jaw member in engaged relation in said guide arms.

4. An ear trimming device of the character described comprising, a body member having a pair of spaced hollow guide arms thereon and a clamping face between said guide arms, said body member also having a channel extending therethrough and opening through said clamping face, a jaw member having a clamping face in coextending opposed relation to the clamping face of said body member and end portions slideable in said hollow guide arms for movement of said jaw member toward and away from said body member, said jaw member being readily disengageable from said guide arms for removal of said jaw member from said body member, a slide movable along the channel of said body member, a knife carried by said slide and movable thereby for cutting engagement with an ear held between the clamping faces of said jaw and body members, and springs disposed in said guide arms and acting on said jaw member for urging the same toward said body member, said springs forming a retaining means for releasably retaining said jaw member in connected relation to said body member and each spring comprising a leaf spring having one end thereof connected with one of said guide arms and another end thereof connected with the corresponding end of said jaw member.

5. An animal ear trimming device comprising, an elongated body member having a pair of longitudinally spaced hollow guide arms thereon and a longitudinal clamping face between said guide arms, said body member also having a longitudinal guide channel therein and an extension slot substantially coextensive with said guide channel and opening therefrom through said clamping face, an elongated jaw member having a longitudinal clamping face in coextending opposed relation to the clamping face of said body member and a longitudinal clearance slot opening through the clamping face of said jaw member, bearing portions on the ends of said jaw member and slideable in the hollow guide arms of said body member for movement of said jaw member relative to said body member for clamping an ear between the clamping faces thereof, spring means mounted in said guide arms and acting on said jaw member to shift the same toward said body member, a bar slideable in the guide channel of said body member and having handle means adapted to be grasped for actuating said bar, a knife, and quick-detachable pin and slot connecting means releasably connecting said knife with said bar for movement thereby along said extension slot with a portion of the

knife projecting into said clearance slot, said knife having a cutting edge on the forward side thereof which extends in rearwardly inclined relation to the longitudinal direction of the cutting movement of said bar for causing said cutting edge to be drawn across said ear with a slicing action.
